ASH TRAY

James E. Gaylor, Sacramento, Calif.

Application April 12, 1954, Serial No. 29,953

Term of patent 14 years

(Cl. D85—2)

To all whom it may concern:

Be it known that I, James E. Gaylor, a citizen of the United States of America, residing at Sacramento, California, have invented a new, original, and ornamental Design for an Ash Tray, of which the following is a specification, reference being had to the accompanying drawing, forming a part hereof.

Fig. 1 is a top plan view of an ash tray, showing my new design;

Fig. 2 is a rear elevational view thereof;

Fig. 3 is a fragmentary side elevational view thereof, on an enlarged scale;

Fig. 4 is a fragmentary front elevational view thereof;

Fig. 5 is a fragmentary top plan view thereof;

Fig. 6 is a cross-sectional view thereof, taken on line 6—6 in Fig. 1; and

Fig. 7 is a fragmentary cross-sectional view thereof taken on lines 7—7 in Fig. 5.

The tray portion has been omitted in Figs. 3 and 4, and the human head portion has been omitted in Figs. 5, 6 and 7 for convenience of illustration.

I claim:

The ornamental design for an ash tray, as shown and described.
